UNITED STATES PATENT OFFICE.

LEO RANNEY, OF JACKSBORO, TEXAS, ASSIGNOR TO STANDARD OIL DEVELOPMENT COMPANY, A CORPORATION OF DELAWARE.

APPARATUS FOR RECOVERING OIL.

Application filed May 7, 1924. Serial No. 711,596.

This invention relates to the recovery from the earth of liquid natural products, such as oil.

Mineral oil is recovered from more or less porous material, such as sand, sand stone, shale, limestone or the like, all commonly called sand, in which the oil has collected and is trapped or held by the characteristics and position of neighboring strata of the earth. The oil bearing sand is found at various depths and invariably lies beneath what is called a cap rock, an essential characteristic of which is its impervious nature causing it to trap and confine beneath it in the porous sand oil, gas and sometimes water. Usually the oil sand lies above a similar impervious bed rock which has prevented penetration of the oil downwardly into other strata.

The usual method of oil recovery consists in sinking a plurality of wells (usually four to six inch casing pipes) to the upper cap rock above the oil bearing sand stratum, setting the casing upon the cap rock, and then 25 drilling a smaller hole through the cap rock into the sand. As before stated, from each well are first collected the gas and oil which are caused to flow because of the pressure of the free gas or the gas absorbed in the oil or contained in the pores of the sand.

Among the several serious problems presented to the operator of such an oil well is the accumulation in the well apparatus of water, paraffin, sand and muck, which pass 35 through the sand into the well and casing. As a result of this accumulation of bottom settling, sand and muck, the tubing, working barrels, pumps, etc. have to be periodically pulled and the wells cleaned out, at 40 great labor expense and loss of productive time.

A second problem presented is the disposition of the gas delivered into the wells and the oil pipe line from the oil bearing sand. 45 Even in an exhausted field there is some gas present, and many methods have been tried in an attempt to save this gas for commercial purposes, all of which methods have been more or less unsuccessful. Among the methods that have been tried is the collection of this gas in gas-proof oil storage tanks, but the gas in these tanks not only exerts a back pressure against the oil, but much gas is lost and also these tanks are a constant source of 55 danger.

A third problem presented is the accumulation of paraffin in the oil bearing sand at the point or points of withdrawal of the oil, and on pumps, valves, working barrels and tubing. As a result of these paraffin accumulations, the valves and tubing, and the sand opening or openings are often closed and the flow of oil into the oil line thereby prevented.

Experience shows that when the upper 65 cap rock is punctured by a well tube, the oil is caused to flow into said tube by the pressure of free gas which may have collected above the oil, but more important, by the continuing pressure of the gas absorbed 70 or held in the oil or trapped in the pores of the sand, and the pressure of which gas is applied more and more to the oil as the latter is withdrawn from the porous material in which it lies. Another force tending 75 to cause flow of the oil to the surface is the hydrostatic pressure of water beneath it. After a time, however, artificial stimuli are necessary to produce a further flow or to increase a weak one. When the 80 flow diminishes, the internal pressure is usually accentuated by the application to the well of a suction or vacuum pump. Recovery sometimes has also been increased in an abandoned, exhausted or dying field by application of compressed air or water under 85 pressure introduced to the porous sand through one or more selected wells to increase the flow from other wells.

The object of the present invention is, 90 therefore, to successfully solve the above and other problems presented in the recovery of oil by means of wells by the separation from the oil, before delivery to the earth's surface, of gas, water, sand and 95 muck, the gas being separately piped to the surface of the earth where it is stored in suitable reservoirs for future commercial use. By separating the sand and muck from the oil practically immediately after delivery into the oil line from the oil bearing sand, the frequent pulling of the tubing, working barrels, pumps, etc., to clean out the same and the wells, is unnecessary.

A further object of the present invention 105 is to prevent the accumulation of paraffin in the oil bearing sands at the oil receiving nipples of the oil line and elsewhere, and the melting of paraffin if it has already so accumulated, by periodically flushing with 110

live steam the oil line and its oil receiving nipples. This steam flushing not only solves the paraffin problem but also serves as a means for heating the oil bearing sand, particularly adjacent the oil receiving nipples, which materially reduces the viscosity of the oil and thereby expedites its flow. At the same time the gas released by the heated oil becomes an additional expulsive force

10 to drive the oil from the sand.

A further object of the invention is to increase the effectiveness of such artificial stimuli, as compressed air and water under pressure, by injecting either of these mediums into the oil bearing sand by means of rows of injection nipples which rows are alternately arranged with rows of oil receiving nipples, that is a row of injection nipples and then a row of receiving nipples.

20 The oil in the oil bearing sand is, therefore, driven to the right and to the left by each row of injection nipples and to the two rows of oil receiving nipples at the sides thereof, thereby materially producing or increasing the flow of oil into the oil line.

Further objects of the invention are in part obvious and in part will appear more in detail hereinafter.

In the drawing, Fig. 1 represents a sectional elevation illustrating one embodiment of my invention; Fig. 2 is a sectional plan view on the line 2—2, Fig. 1; Fig. 3 is a vertical section through one of the control valves.

35 Referring to the drawing, 1 represents a central shaft extending downwardly from the surface of the earth through the overlying strata to the region of the oil bearing porous material, such as sand, sandstone, or the like, said material being generally indicated at 2. The depth of the oil bearing sand varies but in any event the shaft is sunk according to the usual methods of mining to a level adjacent the porous sand, either above or below the same. In the specific arrangement here shown, said shaft terminates below the upper cap rock 3, being provided at its bottom with an enlarged laterally extending portion 1^a which is formed

40 either entirely within the cap rock, or, if it enters the oil sand, is spaced therefrom by impervious material 1^b. While a mine shaft is here illustrated, it will be understood that in some fields a drift mine may be preferable or necessary.

Extending laterally from the upper end portion of shaft portion 1^a and along the upper surface of the upper cap rock 3, is a branch shaft or tunnel 4, from one or both sides of which extend a plurality of substantially parallel tunnels, four such tunnels being here shown which extend from the same side of tunnel 4. In the present embodiment, the first and third of these tunnels, when viewed from left to right in Fig.

2, are the oil receiving tunnels and are indicated by the reference numeral 5, while the second and fourth tunnels are the stimuli injection tunnels and are indicated by the reference numeral 6.

Arranged substantially horizontal within each tunnel 5 is an oil receiving pipe 7 to which oil receiving nipples 8 are connected at suitable intervals by the valves 9. These nipples 8 extend through the upper cap rock 3 down into the oil bearing sand, forming mine walls, the flow through each nipple being controlled by its individual valve. If the sand around the oil receiving nipples is particularly loose, suitable cylindrical screen members may be associated with said nipples to prevent the clogging up of the same with the sand particles.

As shown in Fig. 3, the valves used in the present installation are preferably of the well-known gate type and are installed in cross fittings 9'. Opposite arms of the cross fitting receive the ends of pipes forming part of the oil collecting conduit 10. The lower arm of the fitting is connected to a nipple 8. Other suitable valve connections may be used.

Experience has shown that the oil in the oil bearing sand is forced into the oil receiving nipples 8 of the oil pipes 7 by the pressure of free gas which may have collected above the oil, but more important, by the continuing pressure of the gas absorbed or held in the oil or trapped in the pores of the sand, and in some instances, by hydrostatic pressure. The oil flows through pipes 7 into a substantially horizontally disposed pipe 10 arranged in tunnel 4 and is delivered by the latter pipe into the upper end portion of a separator 11, suitably arranged within the lateral shaft portion 1^a. Horizontally mounted within the casing of said separator just below the inlet of pipe 10 are one or more baffling screens 12, the purpose of which is to agitate the oil falling thereon and effect the release therefrom of some gas absorbed or held thereby. The gas delivered into the separator with the oil and the gas released from the oil by the baffle screens, pass from the separator through the gas pipe line 13 and are delivered thereby to the earth's surface, where the gas is stored in suitable tanks or reservoirs. The saving of this gas for commercial purposes materially increases the financial returns from the oil recovery operations, and inasmuch as the gas is sealed from the branch tunnels and the central shaft at all times, the latter are more comfortable and there is no danger of explosions or otherwise.

The gas pipe line 13 is provided, of course, preferably, adjacent the separator, with a suitable valve 14 for controlling the flow of gas therethrough.

The water, sand and muck delivered into

the separator with the oil fall to the bottom of the separator, from which they may be periodically withdrawn through discharge pipe 15, the passage through which is controlled by a suitable valve 16. The oil, from which the gas, water, sand and muck have been separated, passes from the separator into an inverted siphon 17 and thence into the upper end portion of a suitable sump 18, the purpose of the siphon being to prevent the passage into the sump of gas from the separator. A by-pass 35^a (Fig. 1) is provided for supplying steam from line 35 to the nipples 8. The oil delivered into the sump 18 passes upwardly through a vertically disposed pipe 19 arranged within the sump and thence into a horizontally disposed pipe 20 leading to a suitable pump 21. Connected to said pump is an oil delivering pipe 22 extending through the central shaft 1 to the earth's surface, where the oil is stored in suitable tanks or reservoirs (not shown).

As before mentioned, the oil, with its sand, water, muck and gas content, is forced up into the oil pipes 7 and 10 by the pressure of the gas between the upper and lower cap rocks; sometimes by hydrostatic pressure below the oil, or by the application to the oil bearing sand of artificial stimuli herein-after described. One or more of these forces produces a flow of oil in the pipe line and causes the delivery to the earth's surface of the separated gas and oil. By separating the gas from the oil, the former is saved for commercial purposes, and by separating the water, sand and muck from the oil, the necessity of frequently cleaning out the wells, tubing, working barrels etc., at great expense, is avoided, the water, sand and muck being left at the base of the shaft or being otherwise suitably disposed of.

In order to produce a flow of oil into the oil line or to expedite or increase a weak flow, a vacuum may be placed in the oil line, preferably in a manner so that the separator and sump are cut out and are thus not subjected to the vacuum and need not, therefore, be specially built to withstand it. In the present embodiment, the vacuum line 23 is connected to the oil pipe just before it reaches the separator 11 and to the oil pipe 20 between pump 21 and sump 18. Pipe 20 is provided between the sump and the point of connection with the vacuum line with a suitable valve 24 and pipe 10 is provided between the separator 11 and the point of connection of the vacuum line with a suitable valve 25, which valves enable the sump and the separator to be shut off from the oil line when the vacuum is on. When a vacuum in the line is not necessary, the valve 26 of the vacuum line will be closed, and the oil line valves 24 and 25 open. The pump 21, of course, will be in operation only when necessary to pump oil from the sump or to pro-

duce a vacuum in the line. It is to be noted that when the vacuum is on, the valve of regular oil pump 21 will be bathed in oil, which in a small installation makes an ordinary oil pump suitable for a vacuum pump, thereby obviating the necessity of a regular vacuum pump with valves operated by springs, etc.

If a vacuum is necessary or desirable in the line and there is considerable sand, muck, and water being delivered with the oil into the oil pipes 7 and 10, a suitable collector or reservoir for these foreign contents can be connected to the oil line.

In the specific embodiment here shown, a reservoir 27, suitably arranged within the lateral shaft portion 1^a, is connected by means of a pipe 28 with the oil pipe 10 just before its connection to the vacuum line 23. The sand, muck and water will be collected in this reservoir and can be periodically withdrawn therefrom through the discharge pipe 29 at the lower end thereof, the passage through said pipe being controlled by a suitable valve 30. The pipe 28, by means of which the reservoir is connected to the oil line, will also be provided with a suitable valve 31 for controlling the flow therethrough. This valve will, of course, be closed and the reservoir thus cut off when it is not needed, such as when a vacuum is not on and the separator 11 therefore in use. One of the advantages of separating the water from the oil before passing into the pump 21 is that they will not be churned together and the oil thereby emulsified. In a big operation, a separate pump may be installed for the water, as will be readily understood.

As before stated, experience has shown that the oil will be forced through the oil receiving nipples 9 into the oil pipes 7 by the pressure of free gas which may have collected above the oil, but more important, by the continuing pressure of the gas absorbed or held in the oil or trapped in the pores of the sand, the pressure of which gas is applied more and more to the oil as the latter is withdrawn from the porous material in which it lies. Another force tending to cause flow of oil to the surface is the hydrostatic pressure from beneath it. After awhile, however, these forces fail to produce a flow of oil, or a large or rapid enough flow, and even a vacuum in the line will after a time fail to produce the desired results. Further artificial stimuli are, therefore, resorted to, said additional stimuli usually being in the form of compressed air, gas or water under pressure which are injected into the oil bearing sand, the injection of water being particularly advantageous in fields underlain with salt water.

In order to increase the effectiveness of these artificial stimuli, the compressed air,

gas or water is injected into the oil bearing sand at a plurality of points arranged in substantially parallel rows, as the movement of a fluid through sand or other porous material is much more rapid where a large body of the fluid is moved at one time. In the preferred arrangement, the injection rows and the rows of oil receiving nipples are alternately arranged. For example, a horizontally disposed pipe 32 is arranged in each injection tunnel 6, said pipes being provided with a plurality of suitably spaced injection nipples 33 which extend down through the cap rock 3 into the oil bearing sand, each of said nipples being provided with a suitable valve 33a for controlling the flow therethrough. Compressed air, gas or water under pressure is supplied to these pipes 32 by a pipe 34 connected thereto, which in turn is suitably connected with a source of compressed air, gas or water at the earth's surface, or elsewhere. Thus, in the arrangement shown in Fig. 2, the rows of injection nipples 33 and the rows of oil receiving nipples 9 are alternately arranged. With such an arrangement, the oil in the oil bearing sand will be driven to the right and to the left of each row of injection nipples and to the two rows of oil receiving nipples at the sides thereof. The simultaneous injection of such artificial stimuli at a plurality of points arranged in rows with the rows of oil receiving nipples alternately arranged therewith produces a surprisingly rapid flow of oil which flow can be still further increased, if desired, by a vacuum in the oil receiving line.

If desired, the injection nipples might be so arranged as to extend through the upper cap rock 3 into the oil bearing sand while the oil receiving nipples might extend upwardly through the lower cap rock (not shown) into the oil bearing sand, the force of gravity, with such an arrangement, assisting in producing a flow of oil into the oil line. If a large field is to be operated, the injection nipples, if for water, might be arranged at the margin or the edge of the field so as to force the oil inwardly to the central portion of the field, where the oil receiving nipples might be located, but when compressed air or gas is injected, the injection nipples should be placed near the top of the sand structure and the oil receiving nipples nearer to the edge.

In order to melt paraffin accumulations at the oil receiving nipples 9 and elsewhere, and to prevent the further accumulation of paraffin, the oil line with its oil receiving nipples may be periodically flushed out with live steam.

In the specific embodiment here illustrated, there is arranged within the laterally extending tunnel 4, a steam pipe 35 which is suitably connected to a source of

steam supply, located at the earth's surface or elsewhere. Extending from this steam pipe 35 into each of the laterally extending oil tunnels 5 is a branch pipe 36, the rear end of which communicates with the rear end of the oil receiving pipe 7 in that tunnel. The live steam introduced into these oil receiving pipes 7 will flush in turn the oil receiving nipples as the steam passes through the oil receiving pipes 7 to the oil pipe 10. If desired, the water of condensation in the oil pipe 10 can be separated from the oil before the water and the oil are churned together by the pump 21, if it is operating, and especially so if the oil has a tendency to emulsify.

The flushing of the oil pipes 7 and their oil receiving nipples 8 with live steam not only solves the paraffin problem but also provides a means for heating the oil bearing sand, especially adjacent the oil receiving nipples 8. By so heating the oil bearing sand, the oil therein is rendered less viscous and its flow through the oil bearing sand materially expedited, moreover, the gas released therefrom becomes an added explosive force. In order to more thoroughly heat the oil bearing sand, the oil receiving nipples may be provided with suitable heating devices, such as electrical heaters, containers for dry steam, chemicals, etc.

While I have illustrated in the drawing an arrangement for separating from the oil its foreign content, both fluids and solids and either with or without a vacuum in the line, it will be understood that the particular conditions at any one field may make a vacuum at all times advisable, so that the separator 11 and sump 18 may be omitted. Or, on the other hand, a vacuum may be unnecessary and the vacuum line 23, and pump 21 and reservoir 27 omitted.

Other advantages of the invention will be apparent to those skilled in the art to which it relates.

What I claim is:

1. In a mine gallery installation for recovering oil from an oil bearing stratum, the combination of mine wells, an oil collecting conduit connected to said mine wells, lifting means adjacent the stratum for raising the oil to the earth's surface, and means for separating the oil from emulsion-forming substances before the oil enters the lifting means.

2. In a mine gallery installation for recovering oil from an oil bearing stratum, the combination of mine wells, an oil collecting conduit connected to said mine wells, a separator into which said conduit discharges and arranged adjacent the stratum, pipes connected to the separator for severally withdrawing gas, oil, and solid or liquid substances contaminating the oil, and a pump and pipe line arranged to raise the

separated oil from the separator to the earth's surface.

3. An installation according to claim 2 in which a sump serving as an oil reservoir is arranged between the separator and the pump.

4. Installation according to claim 2, in which a suction line is connected to the oil collecting conduit at a point between the mine wells and the separator, and valve means are provided for cutting said separator and pump out of circuit with the oil collecting conduit.

5. In a mine gallery installation for recovering oil from an oil bearing stratum, the combination of a series of mine wells forming the only inlet for fluids from said stratum to said gallery, an oil collecting conduit connected to said mine wells, a second conduit connected to said mine wells for supplying steam thereto, a separator into which said oil collecting conduit discharges and arranged adjacent the stratum, pipes connected to the separator for withdrawing respectively gas, oil, and solid or liquid substances contaminating the oil, and a pump and pipe line arranged to forward the separated oil to the earth's surface.

6. In the recovery of oil from an oil bearing stratum to which access is gained by a mine shaft, and tunnels excavated at an angle thereto, the combination of mine wells, an oil pipe line disposed within said shaft and tunnels and provided with a plurality of oil receiving nipples entering the mine wells, and a live steam supply line connected to said oil pipe line for flushing out said line and the oil receiving nipples and mine wells.

7. In the recovery of oil from an oil bearing stratum to which access is gained by a mine shaft, and tunnels excavated at an angle thereto, the combination of an oil pipe line provided with a plurality of substantially parallel rows of inlet openings for receiving oil from the oil bearing stratum, and a second pipe line provided with a plurality

of substantially parallel rows of discharge openings for introducing a fluid medium into the oil bearing stratum so as to facilitate the flow of oil to said oil receiving openings, the rows of inlet openings and the rows of discharge openings being alternately arranged.

8. In the recovery of oil from an oil bearing stratum to which access is gained by a mine shaft and tunnels excavated at an angle thereto, the combination of an oil pipe line disposed within said mine shaft and tunnels and provided with a row of oil receiving nipples extending into the oil bearing stratum for receiving oil therefrom, and a second pipe line also disposed within said mine shaft and tunnels and provided with a row of injection nipples for introducing a fluid medium into the oil bearing stratum so as to facilitate the flow of oil to said oil receiving nipples.

9. In a mine gallery installation for recovering oil from an oil sand, the combination of a series of mine wells, an oil collecting conduit connected to said mine wells, a second conduit also connected to said mine wells for supplying steam thereto, a pipe in generally spaced parallel relation to the oil collecting pipe and having branches entering the oil sand, and means for supplying a flow stimulating agent to said branches.

10. Installation according to claim 9 in which pipes for collecting oil and pipes for supplying the flow stimulating agent are arranged respectively in several pairs of generally parallel galleries.

11. In a mine gallery installation for recovering oil from an oil bearing stratum, the combination of a stimulus line, an oil collecting line, a series of openings sealed from the gallery and extending into the stratum, said openings being connected alternately to the stimulus line and the oil collecting line.

In testimony whereof I hereby affix my signature.

LEO RANNEY.
